UNITED STATES PATENT OFFICE.

WILLIAM R. K. STANFORD, OF LAWLEY, ALABAMA.

KITCHEN-RANGE.

1,061,699.

Specification of Letters Patent.

Patented May 13, 1913.

Application filed December 18, 1911. Serial No. 666,413.

To all whom it may concern:

Be it known that I, WILLIAM R. K. STANFORD, a citizen of the United States, residing at Lawley, in the county of Bibb and State 5 of Alabama, have invented a new and useful Kitchen-Range, of which the following is a specification.

This invention relates to kitchen ranges of that type wherein the fire pot and ash 10 pit are separated from the oven and its flues by a metal partition on which the fire pot and grate are partly supported.

One of the objects of the invention is to provide means applicable to such a stove 15 for mingling hot air with the products of combustion passing off from the fire pot to consume the smoke therein.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed can be made within the scope of what is claimed, without departing from the spirit of the invention.

In the accompanying drawings the preferred form of the invention has been shown.

In said drawings:—Figure 1 is a longitudinal section of a stove constructed in accordance with the present invention. Fig. 2 is a section through the range on the line 35 A—B Fig. 1, a portion of the fire pot being removed.

Referring to the figures by characters of reference 1 designates the fire pot of the stove separated by the partition 2 from 40 the smoke flues 3 of the oven. This partition does not, of course, extend up to the top of the stove, the usual space being provided for the direct draft to the smoke pipe 4. A damper 5 is shown for controlling the direct and indirect draft of the oven, but this forms no part of the present invention.

The partition 2 is provided with ledges 6 on which rests the grate 7 of the fire pot. In the partition 2 is formed a series of channels 55 8 extending from below the grate to a point close to the top of the partition. The top of this partition is provided with a flange 9 on which rests the flanged upper edge of the fire pot 1. Openings 10 are formed in this flange and at the upper ends of the channels

8 and these openings form nozzles through which air may flow into the space below the stove top and above the fire pot. By thus forming an air space between the partition 2 and the fire pot sufficient air is heated and 60 directed through the openings 10 to combine with and burn the smoke contained in the products of combustion and as the jets of air issue in the direction in which the products of combustion are traveling, the suction 65 created by the draft of the stove is sufficient to maintain a proper flow of this heated air. It is to be understood of course that the particular method of forming the air channels can be changed according as the invention 70 is applied to sheet metal or cast metal ranges.

What is claimed is:—

1. In a stove, the combination with opposed partitions having inwardly directed top flanges, of a fire pot bearing downwardly 75 on the flanges and supported thereby between the partitions, there being openings within the contacting portions of the flanges and fire pot and constituting nozzles, there being longitudinal depressions or channels 80 within the partitions and extending from the openings downwardly to points below the fire pot.

2. In a stove, the combination with oppositely disposed partitions having inwardly 85 directed supporting flanges at their upper edges, of a fire pot interposed between the partitions and having outstanding flanges bearing downwardly on the flanges of the partitions, there being openings through the 90 contacting flanges, said partitions having longitudinally extending depressions or channels extending from the openings in the flanges and downwardly to points below the fire pot to receive air from the ash chamber 95 under the fire pot.

3. In a stove, oppositely disposed partitions constituting walls of an ash compartment, said partitions having inwardly directed top flanges, a fire pot having outstanding flanges supported by the flanges on the partitions, there being openings through the flange of one of the partitions and the adjacent flange of the fire pot, said partition having longitudinal depressions in one face 100 thereof forming channels communicating with the openings in the flange and with the ash compartment below the fire pot, said fire pot having its outer walls converging 105 downwardly to form an air space between 110

the fire pot and the partitions, spaced ledges upon the partitions, and a grate supported by the ledges, there being air passages between the ledges, said longitudinal channels or depressions extending below the grate supporting ledges.

In testimony that I claim the foregoing as

my own, I have hereto affixed my signature in the presence of two witnesses.

WILLIAM R. K. STANFORD.
